UNITED STATES PATENT OFFICE.

JOHN E. McDANIEL, OF MADISON MILLS, OHIO.

GOVERNOR ATTACHMENT.

No. 910,409.

Specification of Letters Patent.

Patented Jan. 19, 1909.

Application filed July 14, 1908. Serial No. 443,495.

To all whom it may concern:

Be it known that I, JOHN E. McDANIEL, a citizen of the United States, residing at Madison Mills, in the county of Fayette, State of Ohio, have invented certain new and useful Improvements in Steam-Governor Attachments; and I do hereby declare the following to be a full, clear, and exact description of the invention, such as will enable others skilled in the art to which it appertains to make and use the same.

This invention relates to steam governors, and has for its object to provide a simply constructed attachment whereby the speed of the engine may be increased or decreased by manipulating the valve rod of the governor.

With these and other objects in view the invention consists in brackets adapted to be attached to the frame of a governor, a rock shaft having connecting means whereby the rocking of the shaft will change the position of the valve rod of the governor, an arm connected to the rock shaft, and yieldable means coupled to the arm whereby the rock shaft may be adjusted and yieldably supported to change the position of the valve rod of the governor, and thus regulate the speed of the engine.

The invention further consists in certain novel features of construction as hereafter shown and described, and then specifically pointed out in the claim, and in the drawings illustrating the preferred embodiment of the invention, Figure 1 is a view from one side of a conventional steam engine governor with the improved device applied. Fig. 2 is a view of the parts shown in Fig. 1 from another side. Fig. 3 is a plan view in section on the line 3—3 of Fig. 2. Fig. 4 is a perspective view of the valve rod and a portion of the shipper mechanism.

The improved device may be applied without material structural changes to steam engine governors of various forms and constructions, and it is not desired therefore to limit the invention in its operation to any specific form of governor, and for the purpose of illustration the improved device is shown applied to a conventional governor in which the base or valve chamber is represented at 10, the arching frame supporting the valve rod at 11, the gearing whereby the valve rod is rotated at 12, the valve rod at 13 and

the governor balls including the supporting framework thereof as a whole at 14, these parts being of the usual construction.

Attached to the frame 11 at one side is a bracket 15 and attached to the frame 11 at the opposite side is a similar bracket 16, the brackets supporting a shaft 17 which extends transversely of the frame 11 and is spaced therefrom as shown. The shaft 17 is provided with a laterally extending forked member 18 which bears upon opposite sides of the rod 13 and engages between spaced collars 19—20, so that the rocking or oscillation of the shaft 17 will cause the rod 13 to be moved upwardly and downwardly as hereafter explained.

Connected centrally thereof to the shaft 17 is an arm 21, and formed upon the bracket 16 is a rigid arm 22, and connected respectively at one end to the arm 22 at its ends are springs 23—24, the opposite ends of the springs being connected to the arm 21 above and below the shaft 17 so that the springs operate to hold the arm 21 yieldably in a vertical position, the object to be hereafter explained.

Connected to some stationary portion of the engine, as for instance to the steam chest indicated at 25, is a toothed segment 26 upon which a lever 27 is pivoted at 28 near one end, the lever being provided with a spring actuated pawl 29 engaging in the teeth of the member 26 and actuated by a hand grip 30 of the usual form. By this means the lever may be adjusted to any required point relative to the toothed segment and locked there- to as required.

Connected between the upper end of the arm 21 and the lever 27 above its pivot 28 is a yieldable member formed with a section of spring 31 and a rod 32, and likewise connected between the lower end of the arm 21 and the lower end of the lever 27 is a yieldable member formed of a section of spring 33 and a rod 34. By this arrangement a rocking motion may be imparted to the rod 32 by the movement of the lever 27, the adjustment of the arm 21 thus corresponding to the adjustment of the lever, the springs 31—33 permitting the arm 21 to be oscillated independently of the lever to a limited extent so that the rod 13 may be moved vertically through the influence of the ball mechanism 14 independently of the position of the lever

27 owing to the yieldable nature of the springs 23—24 and 31—33, while at the same time by adjusting the lever 27 the position of the rod 13 relative to the valve 35 in the casing 10 may be changed to enable the speed of the engine to be correspondingly changed, as hereafter explained.

- By setting the lever 27 in a vertical position the arm 21 will likewise be disposed in
- 10 a vertical position and the arm 16 disposed in a horizontal position or at its intermediate adjustment, so that the movement of the rod under the influence of the governor balls will be normal, and when the parts are left in this
- 15 position the speed of the engine will be controlled in the ordinary manner. If however, the speed is to be increased the lever 27 will be adjusted to elevate the arm 16 which will correspondingly elevate the rod 13 and open
- 20 the governor valve 35 thus permitting more steam to pass to the governor, and this adjustment of the rod 13 does not affect the operation of the governor which still continues to control the speed at the new rate,
- 25 and if the speed is to be reduced below the normal the lever 27 is adjusted in the opposite direction to cause the arm 21 to rotate the shaft 17 and depress the arm 16 and thus correspondingly depress the rod 13 and close
- 30 the governor valve to a corresponding extent and thus permit a less quantity of steam to pass and correspondingly reducing the speed, the governor continuing then to control the speed in the same manner.
- 35 By providing a plurality of the notches in the segment 26 it will be obvious that the position of the lever may be adjusted to any required extent and thus provide for any required speed of the engine.
- 40 The speed of the engine may thus be easily controlled without reference to the throttle

valve, and controlled in a much more accurate manner.

The adjustments may be very delicately made and very slight differences in speed 45 produced.

The improved device is simple in construction, can be readily applied to governors of various forms and sizes by making slight and immaterial changes in the forms of the brackets 50 15—16 to adapt them to the differences in the forms of the frames of the governors, and as these slight changes do not affect the construction of the device it is not deemed necessary to illustrate the various forms of 55 brackets necessary to be employed.

What is claimed, is:—

The combination with a steam engine governor, including a valve casing, the valve, the valve rod, the means for automatically 60 controlling the position of the valve rod, and a frame for supporting the valve rod controlling means, of brackets spaced apart and connected to said frame, one of said brackets having oppositely extending rigid arms, a 65 shaft mounted for oscillation in said brackets, coupling means between said shaft and the valve rod, an arm connected to said shaft and partaking of its motion, springs connected between the arm of said shaft and the 70 rigid bracket arms at opposite sides of the shaft, a swinging lever, means for locking said lever in any required position, and yieldable coupling means between said lever at opposite sides of its pivot and the arm connected to said shaft at its opposite ends.

In testimony whereof, I affix my signature, in presence of two witnesses.

JOHN E. McDANIEL.
